UNITED STATES PATENT OFFICE.

LUDWIG O. HANSON, OF MILWAUKEE, WISCONSIN.

MOUTHPIECE FOR WIND INSTRUMENTS.

No. 799,730.

Specification of Letters Patent.

Patented Sept. 19, 1905.

Application filed February 27, 1905. Serial No. 247,409.

To all whom it may concern:

Be it known that I, LUDWIG O. HANSON, residing in Milwaukee, in the county of Milwaukee and State of Wisconsin, have invented 5 new and useful Improvements in Mouthpieces for Wind Instruments, of which the following is a description, reference being had to the accompanying drawings, which are a part of this specification.

10 This invention relates to mouthpieces for wind instruments of the trumpet or horn type, such as the bugle, cornet, French horn, euphonium, trombone, &c., and has for its object to obviate the indirect wind-passage 15 in such mouthpieces by providing a wind-passage which will be in direct line with the flow of air from the mouth of the performer to the wind-passage of the instrument.

10 The distinctive feature of the invention is 20 its wind-passage formation, wherein the throat has its upper wall in direct alinement with the upper wall of the bowl.

It is quite generally understood and admitted by most performers of the cornet that 25 when playing, especially in the upper register, the tendency is to blow toward the top of the bowl of the mouthpiece. Consequently in mouthpieces as at present constructed much energy is wasted on account of friction 30 caused by the column of air striking the walls of the bowl or cup before entering the outlet or throat, thereby necessitating more pressure on the upper lip and overtaxing and weakening the embouchure to such an extent 35 that partial paralysis of the seventh pair of nerves frequently results.

This invention is designed to overcome 40 these objections by providing a throat which extends in a direct line between the vibrating upper lip of the performer and the wind-passage of the instrument.

With the above and other objects in view the invention consists in the mouthpiece of the construction herein shown and described 45 and the equivalents thereof.

Referring to the accompanying drawings, in which like characters of reference indicate the same parts in the several views, Figure 1 is a side elevation of a mouthpiece for wind 50 instruments constructed in accordance with this invention. Fig. 2 is an end elevation thereof, and Fig. 3 is a longitudinal vertical sectional view thereof.

In the drawings the mouthpiece is shown 55 to be provided with the usual tapering stem 4 for fitting into the wind instrument and a

bowl or cup 5 on its end against which the lips of the performer are pressed during the operation of the instrument, the external shape of the mouthpiece being symmetrical 60 and similar to mouthpieces of the usual construction. The internal construction of the mouthpiece, however, instead of having a horizontal throat leading from the central portion of the bowl, as usual, has the flaring 65 throat 6, arranged on an incline, so that it leads from the uppermost portion of the bowl, which is made with a straight upper wall 7 to a line with the upper wall of the throat 6, the other walls of the bowl being curved to the 70 junction of the throat therewith instead of being symmetrical in shape. In a mouthpiece with a wind-passage of this construction the upper wall of the throat being in direct alinement with the upper wall of the 75 bowl and forming a continuous wall therewith, the throat is on a straight line from the vibrating upper lip of the performer to the wind-passage of the instrument, so there is no deflecting-wall in the path of the air, and 80 consequently less air-pressure is necessary to produce a large tone, and the softest whisper will not be lost by reflection, but will be reproduced as clear as other tones. On account of the ease in producing the tone and 85 manipulating the instrument as the result of the direct wind-passage of this mouthpiece the performer is assured a clearer and better quality of tone, as well as a perfect intonation 90 of the instrument.

It is not to be understood that this invention relates merely to the connection of the throat at one side of the center of the bowl, but it is also necessary that such throat should have one of its walls in direct alinement with a wall of the bowl, so that the two may have a common straight wall, and the throat may therefore extend in a straight line from the vibrating upper lip of the performer to the wind-passage of the instrument. 95

100 What I claim as my invention is—

1. A mouthpiece for wind instruments having its throat connecting with its bowl at the extreme edge of the bowl, with a wall of the throat in alinement with a wall of the bowl. 105
2. A mouthpiece for wind instruments having the usual symmetrical external shape and having its flaring throat inclined and connected with the bowl at one side of said bowl, the bowl being provided with a straight wall 110 on that side in direct alinement with a wall of the throat and the other walls thereof curv-

ing toward the junction of the throat with the bowl.

3. A mouthpiece for wind instruments having a bowl with its upper wall straight and its other walls converging thereto, and the throat extending from the bowl with its upper wall in direct alinement with the straight wall of the bowl, so that said throat forms an unobstructed direct connection between the

vibrating upper lip of the performer and the wind-passage of the instrument.

In testimony whereof I affix my signature in presence of two witnesses.

LUDWIG O. HANSON.
